UNITED STATES PATENT OFFICE.

HENRY W. STEWART, OF LONG BEACH, CALIFORNIA.

PUMP-VALVE SEAT AND LINER PULLER.

Application filed October 8, 1923; Serial No. 667,255.

To all whom it may concern:

Be it known that I, HENRY W. STEWART, a citizen of the United States, residing at Long Beach, in the county of Los Angeles and State of California, have invented new and useful Improvements in Pump-Valve Seat and Liner Pullers, of which the following is a specification.

This invention relates to tools and more particularly to a valve seat puller.

An object of the present invention is to provide a simple, inexpensive, substantial and effectively operable device for readily pulling bushings or sleeves or other mechanical elements from their mountings. An object especially is to provide a device to facilitate the removal of valve seats from their casings.

Other objects and advantages will be made manifest in the following specification of an embodiment of the invention illustrated in the accompanying drawings, wherein:

Figure 1 is a perspective of the device, a portion of its stem being broken away.

Fig. 2 is a side elevation and vertical section showing the operation of the device.

Fig. 3 is a top plan and cross section.

The tool of the present invention consists of a body 2 here shown as cylindrical and of such dimensions that it is adapted to be slipped down through a valve seat S in the form of a sleeve fitted in the shell or casing, C. It becomes necessary to remove the valve seat for renewal and for regrinding or for other purposes, and in such event the puller body 2 is passed down through the valve seat so as to position sliding blocks 3 below the lower edge of the valve seat.

These blocks 3 are provided with outwardly extending hook ends 3^a which, in their effective position extend to the edge of the seat S. The blocks are provided with longitudinally extending beads 3^b engaging complementary guide channels 4 which incline upwardly and inwardly toward the top of the body 2, with the result that when the blocks 3 move, they have an outward or inward movement concurrently with their endwise movement. When the puller body 2 is passed down into the valve seat, the lower ends of the blocks 3 engage the valve seat and the blocks are forced inwardly so that their hooks 3^a will clear and pass down in through the valve seat.

For the purpose of pulling the blocks and

the body 2, and with it the valve seat S, the body is provided with a stem or shank 5 which is threaded into the body 2 and passes freely through a yoke 7 which, in the inverted position, bears down on the casing C at each side of the valve seat S. A hand wheel 8 is threaded on the upper end 6 of the stem 5, and when the hand wheel is turned it causes a relative upward movement of the puller so that the hooks on the blocks 3 come up against the lower edge of the valve seat S and this is positively gripped and pulled upwardly concurrently with the upward movement of the puller body 2.

A feature of the invention is that after the parts of the puller have been assembled, the stem 5 serves as a guard limiting the upward movement of the hook blocks 3 and these are therefore prevented from being dislodged and lost. The blocks of their own weight slip down and outward after they clear the valve seat when the puller is being inserted. Therefore the blocks automatically assume an expanded position so that the hooks will engage the lower end of the valve seat as the puller body is forced upward by the turning of the hand wheel 8.

The slots 4 forming the guideways for the blocks 3 terminate within the lower end of the body 3 so as to provide stop shoulders 4^a against which the lower ends of the hook blocks solidly rest when the puller body is forced upwardly in the extracting operation.

Further embodiments, modifications and variations may be resorted to within the principle of the invention.

What is claimed is:

1. A valve seat and liner puller comprising a body having a shank with a threaded portion, a bridge-forming element slidably mounted on the shank and adapted to bear on a primary supporting part in which the valve seat or liner is mounted, means on the upper end of the shank to engage the said bridge-forming element and operative to pull the said body, and hook devices slidably mounted on the outside of said body and adapted to automatically move to an effective position below the end of a valve seat or liner to be pulled.

2. A valve seat and liner puller comprising a body having a shank with a threaded portion, a bridge-forming element slidably mounted on the shank and adapted to bear

on a primary supporting part in which the valve seat or liner is mounted, means on the upper end of the shank to engage the said bridge-forming element and operative to pull the said body, and hook devices slidably mounted on the outside of said body and adapted to automatically move to an effective position below the end of a valve seat or liner to be pulled; said hook devices including blocks mounted for inward and outward and longitudinal movement in the said body.

3. A valve seat and liner puller comprising a body, means for imparting an upward movement to said body, and hook devices slidably mounted in inclined grooves formed upon said body and being adapted to engage beneath a liner or valve seat to be pulled.

4. A valve seat puller comprising a body portion adapted to pass down through the valve seat to be pulled, means for effecting an upward, positive movement of the inserted body portion, and hook blocks mounted in the said body portion and adapted to shift outwardly concurrently with a longi-

tudinal movement to an effective position to grapple the lower end of the seat to be pulled, the body being provided with guideways arranged obliquely as to the axis of the body and in which the blocks are slidably mounted.

5. A valve seat puller comprising a body portion adapted to pass down through the valve seat to be pulled, means for effecting an upward, positive movement of the inserted body portion, and hook blocks mounted in the said body portion and adapted to shift outwardly concurrently with a longitudinal movement to an effective position to grapple the lower end of the seat to be pulled, the body being provided with guideways arranged obliquely as to the axis of the body and in which the blocks are slidably mounted, the said guideways terminating in shoulders against which the sliding blocks are firmly supported to take the resistance when pulling a valve seat.

In testimony whereof I have signed my name to this specification.

HENRY W. STEWART.
